[57] CLAIM

The ornamental design for a holder for an artichoke, as shown.

DESCRIPTION

FIG. 1 is a perspective view of a holder for an artichoke showing my new design;

FIG. 2 is a rear view, partially cut-away to better illustrate the design of the inner restraining portion;

FIG. 3 is a top view;

FIG. 4 is a right side view. The left side being a mirror image thereof;

FIG. 5 is a bottom view; and,

FIG. 6 is a front view.

FIG. 1

FIG. 2

FIG. 3

FIG. 4

FIG. 5

FIG. 6
